UNITED STATES PATENT OFFICE

BENJAMIN W. FREEMAN, OF CINCINNATI, OHIO, WILLIAM S. HERSCHEL, OF ST. LOUIS, MISSOURI, AND HERBERT E. PATTERSON, OF COLUMBUS, OHIO, ASSIGNEES TO THE LOUIS G. FREEMAN COMPANY, OF CINCINNATI, OHIO, A CORPORATION OF OHIO.

MACHINE FOR MARKING, ORNAMENTING AND CEMENTING SHOES

Application filed June 28, 1927. Serial No. 202,107.

Our invention relates to machines and processes for marking, or ornamenting gluing, pasting and cementing shoes, and leather goods.

In the art of making shoes, with the many changes in styles of ladies' shoes, particularly in which highly ornamented effects are desired, the making of the uppers often requires much hand labor which it is our desire to minimize. Further, it is our object to provide a machine for making the manufacture of shoes having such decorated effects much more accurate than has heretofore been possible.

In making a shoe, for example, which has an ornamental portion attached to the upper the present method of manufacture requires the operator to apply adhesive to the ornamental portion, or to the shoe or to both the portion and the shoe, the application of the portion to the shoe upper and the firm pressing down thereof so that the portion will remain in position prior to the insertion of the stitches which may later be applied to hold the decoration permanently in position.

It is an object of our invention, as illustrated in the particular type of machine disclosed, to provide a machine which will automatically apply adhesive to the portion of the upper to which the decoration is to be applied. In combination with the automatic cementing machine it is our object to provide a gauging device which will materially aid in the accurate positioning and aligning of the parts to be cemented together.

We further have, as our object, the provision of a clamp and hold down plate associated preferably with the gauging device which also may be adapted to position or align the parts to be attached. While we have illustrated a die and gauging device which assists in the attachment and positioning of a decorative portion to a shoe upper, other modifications in which different types of dies may be used, the placing of ornamental designs in different positions on shoe uppers, and the achieving of other types of work may be accomplished by varying the kind of the dies and of the gauging, clamping and supporting devices.

Another object is the provision of a machine for ornamenting or marking shoe elements in a more satisfactory manner than has heretofore been possible. Previously to the best of our knowledge and belief, no machine for ornamenting or cementing has been provided with means for holding work which often became displaced or was moved. It is also an object to provide means for holding down work to be operated on which will also prevent the displacement of the work by the dies after an impressing operation. When the machine is used for cementing, the well and feed roller associated therewith is filled with adhesive, but upon removing the adhesive and filling the well with some marking material, designs of predetermined size and shape may be applied to shoe elements in an exceedingly simple manner.

The above and other related objects to which reference will be made during the ensuing disclosure we accomplish by the certain arrangement and combination of parts of which we have shown a preferred embodiment.

Referring to the drawings:

Figure 1 is a plan view of the machine with the cementing and marking platen in closed position.

Figure 2 is a side elevation of the machine showing the platen elevated.

Figure 3 is a bottom plan view of the marking or cementing die.

Figure 4 is an end elevation of the die shown in Figure 3.

Figure 5 is a front elevation of the gauge plate and hold down plate assembly showing the hold down plate in open position.

Figure 6 is a plan view of the gauge plate and hold down plate assembly in closed position with shoe elements in position to be operated on, shown in dotted lines.

Figure 7 is a side elevation of the assembly shown in Figure 6.

Figure 8 is a plan view of the particular shape of shoe element for which the particular die, gauge and hold down plate illustrated herein have been designed.

Figure 9 is a plan view of a decorating strip which may be applied to the shoe element and

for which the die, gauge and hold down plate are also specially designed.

Figure 10 is a side elevation of the machine with the pressure platen in operating position.

We have shown the machine having a frame 1 with a fixed base plate 2 which is provided with some means for aligning the work positioning plate thereon such as the pins or studs 3 which register with holes or depressions in the work positioning plate. The pressure platen is indicated at 4 having bosses 5 and 6 in which are pivotally mounted the arms 7 and 8 respectively on which the pressure platen is carried. The mechanism for operating the pressure platen is preferably by a foot treadle. The arms 8 may be fixedly mounted on a shaft 9 journalled in the machine frame and a gear segment 10 may be mounted on the shaft 9. Another gear segment 11 mounted on a shaft 12 is also journalled in the machine frame and the segment 11 engages the gear segment 10. The gear segment 11 may have an aperture 11a therein in which a stud is secured and the stud may have attached to it, a treadle rod indicated at 11b, actuatable by a foot treadle and usually so spring tensioned that with its release the platen will move to elevated position. We have not shown the foot treadle attachment as any means for rocking the shaft 9 will serve to move the platen from open to closed position.

We have indicated a handle 15 which will serve for moving the platen from its open to its closed position, although, as noted, I prefer to operate the machine with a foot treadle. The shaft 9 may be provided with a weight 16 which extends out at the back of the machine and tends to counterbalance the weight of the platen 4. The use of a weight is merely a mechanical expedient for counterbalancing the platen and other mechanical means such as springs may be used to accomplish a similar purpose.

Bosses 17 extend out from the rear of the machine in which arms 18 which carry the fountain and feed roller assembly are pivotally mounted. On the arms 18 we have shown a supply hopper 19 having rotatably mounted therein a feed roller 19a. Springs are disposed as indicated at 20, to tension the feed roller and hopper assembly so that it will be resiliently pressed upwardly into engagement with the die carried by the platen 4.

In order to rotate the feed roller at the same rate at which the die engages it, we have provided driving rollers 20a on ends of the shaft 21 which carry the feed roller. The driving rollers 20a during the elevated position of the platen 4 engage tracks 22 mounted at the side edges of the lower face of the platen so that during the initial movement of the platen from its uppermost position, as indicated in Figure 2, until such time as the

uppermost end of the tracks are moved out of engagement with the drive rollers the rate of rotation of the feed roller is such that the material from the hopper is evenly distributed on the die.

In order to prevent the feed roller and hopper from springing upwardly at the time when the tracks of the platen disengage the drive rollers and to make the working parts more accessible, we have provided a curved arm 23 mounted on a shaft 24, on which the arms 18 are fixedly mounted. The curved arm 23 carries a roller 24a which, during the upward movement of the platen, is not in engagement with any guiding device but which, when the tracks of the platen disengage the drive rollers, engages a cam groove 25 in the counterbalancing weight 16.

The machine is designed so that the feed roller and hopper may be readily adjusted or removed and so that the platen 4 will at some stage of its movement be readily accessible for the interchanging of dies carried thereon.

The die on which the material from the hopper is spread is mounted on a die base plate 26 which is removably mounted on the lower side of the platen 4. The die plate has a pin 27 extending from it which seats within an aperture 28 in the platen 4 and a locking handle 29 pivotally mounted on the upper surface of the platen has a locking portion 30 which engages a slot in the pin 27. The die plate 27 may be aligned with the platen with suitable registering devices such as the pins 29a which seat within apertures in the platen. The die may be of desired kind and size. We have in our illustrations shown a die which is adapted for use for cementing thin strips such as is indicated at 31 in Figure 9 to the upper shoe element indicated at 32 in Figure 8. The die consists in this instance of a pair of thin plates 33 shaped similarly to the strip 31 and attached to the die base plate with screws 34.

For supporting the work we have provided a detachable assembly having a work supporting plate 35 with apertures 36 which register with the mounting studs 3 of the base plate 2. On the plate 35 we have shown guide strips 37 which are attached to the plate 35. These strips serve as guiding abutments against which the edges of the work to be operated on may be placed. We have indicated in Figure 8 how a shoe element such as we have indicated by 32 may be aligned on the work supporting plate 35. The work, having been positioned, is held in position by the clamping plate 38 which is articulated to the work supporting plate 35, and also preferably has springs 39 which assist in the movement of the clamping plate upwardly into the position indicated in Figures 3 and 5 with the return stroke of the platen. The plate 38 is shown with cut-out portions 39

which correspond with the shape of the piece 31 to be applied and also allow clearance for the guide strips 37.

For moving the clamping plate to open and closed position, we have shown a curved arm 38a pivotally mounted in bosses 38b. A lower portion of the arm 38c extends down as indicated in Figure 2 so that a foot treadle attachment may be secured in the arm. We have indicated a hole 38d in the arm which may be used for attachment to a treadle member by which the clamping plate may be moved from the open position in Figure 2 to the closed position indicated in Figure 10. After the work is positioned on the supporting plate the clamping plate is brought against the work acting as a hold down plate and it may then be used to position a strip such as we have indicated at 31 which may be inserted in the cut-out portions 39 and thus positioned on the work. The strips may also be positioned with relation to the imprint of the adhesive or marking material on the work without positioning the strip with relation to the cut-out portions. The dies 33 may be cleaned off and used as pressure plates to hold the strips in firm contact with the work though such a use requires a cleaning off of the dies after each cementing operation and normally the strips may be secured in position by manual pressure.

In order to explain the varied usefulness of the machine let us assume that the machine is to be used for applying a strip 31 such as is indicated in Figure 9 to a shoe upper 32 such as is indicated in Figure 8. We have shown two shoe parts 32 on the work supporting plate 35 where they are properly positioned by being moved into engagement with the edges of the guide strips 37. The clamping plate 38 is then moved down to hold the work in this position and the platen 4 carrying the die base plate 26 is moved from open to closed position. The feed roller 19a during this cycle of movement deposits a layer of adhesive on the dies 33 which is deposited on the work when the dies 33 pass through the cut-out portions 39 in the clamping plate 38. After a layer of adhesive has been applied, the platen is moved back to open position and the strips to be attached to the work are inserted in the cut-out portions 38 and properly positioned on the work. While the clamping plate is still in position on the work the operator may smooth down the strips by extending her fingers through the cut-out portions, or the clamping plate may be allowed to move back to open position and the strips may be positioned on the work subsequently.

If the machine is to be used for marking only and marked impressions of such shape as are shown in the strips 31 are to be applied to the work, the supply hopper is previously filled with the marking material. The work

is positioned in a similar manner on the supporting plate and the clamp and platen are moved to closed position as in the formerly described cycle of operations. When used for marking the feed roller will deposit a coating of marking material on the dies 33, which, as will be apparent, will be transferred to the work when the dies 33 pass through the cut-out portions 39 of the clamp 38. When used for marking the clamping plate need not have the auxiliary usefulness of a positioning plate.

Another usefulness of the machine is for marking work to which previously cemented strips are to be applied. If the strips to be applied have been previously coated with adhesive, the work may be marked and the strips then applied on the marked portions either with or without the clamping plate in position. It will also be practical to hold down work and then apply previously coated strips to the work, using the apertures in the hold down plate to position the applied strips on the work. Dies such as we have indicated may then be used to firmly press down the applied strips on the work in which case the material applying roll need not be used.

While the machine which we have described will serve other useful purposes in the art it is designed primarily for marking and cementing and positioning work. With one machine different sizes and kinds of dies, clamping plates and work supporting plates may be provided which may be readily applied interchangeably. Where hand labor has been the only practical method of doing this type of work we have now provided a machine which will save much labor and increase the accuracy and neatness of the work done.

Having thus described our invention what we claim as new and desire to secure by Letters Patent is:

1. In a machine of the class described having members relatively movable, one with relation to another, means for supporting work to be operated on detachably mounted on one of the members, and dies with means for applying thereto material to be impressed on the work, detachably mounted on one of the members having a relative movement with relation to the first noted member, and means associated with said work support for holding down work after said work has been operated on.

2. In a machine of the class described having members relatively movable, one with relation to another, means for supporting work to be operated on detachably mounted on one of the members, and dies with means for applying thereto material to be impressed on the work, detachably mounted on one of the members having a relative movement with relation to the first noted member, and means associated with said work support for holding

- work to be operated on, said means providing means for positioning a piece to be attached to the work subsequently to the impression thereon of the material noted.
3. In a machine of the character specified having members relatively movable, one with relation to another, means for supporting work to be operated on detachably mounted on one of the members, and dies with means for applying thereto material to be impressed on the work, detachably mounted on one of the members having a relative movement with relation to the first noted member, and means associated with said work supporting plate for holding down work to be operated on, and said means for supporting work having associated therewith means for assisting in the accurate positioning of work on said supporting devices.
4. In a machine of the character specified having members relatively movable, one with relation to another, means for supporting work to be operated on detachably mounted on one of the members, and dies with means for applying thereto material to be impressed on the work, detachably mounted on one of the members having a relative movement with relation to the first noted member, and means associated with said work support for holding work to be operated on, said means providing means for positioning a piece to be attached to the work subsequently to the impression thereon of the material noted, and said work supporting means having associated therewith means for assisting in the accurate positioning of work on said support.
5. A shoe ornamenting machine having detachable work supporting means, means for positioning work on said work support, means for indicating the proper position for a piece to be applied to said work, and means for pressing the piece against said work.
6. A machine of the character specified having a detachable work support, means for impressing material on said work, and means having an opening through which said impressing means passes for indicating the proper position for a piece to be applied to said work subsequent to the impression of the material thereon.
7. A machine of the character specified having detachable means for supporting work to be operated on, means for impressing material on said work, and means for indicating the proper position for a piece to be applied to said work subsequent to the impression of the material thereon, and said last mentioned means comprising a member having at least one aperture therein through which said means for impressing material on said work may be extended.
8. A machine of the character specified having work supporting means, means for impressing material on said work, and means through which said impressing means passes for holding down work on said means for supporting work subsequent to the impression operation.
9. A machine of the character specified having detachable work supporting means, means for impressing material on said work, and means for holding down work on said work supporting means, said last mentioned means comprising a member having at least one aperture therein through which said means for impressing material on said work may be extended.
10. A machine of the character specified having detachable work supporting means, means for impressing material on said work, and means for holding down work on said work support, said holding means having at least one aperture therein through which a piece to be applied to the work subsequent to the impressing operation may be accurately positioned.
11. A shoe ornamenting machine having work supporting means, detachable means for impressing material on said work, means having edge portions arranged for accurately indicating the proper position for a piece to be applied to the work subsequently to the impressing of the material thereon.
12. A shoe ornamenting machine having work supporting means, detachable means for impressing material on said work, means having edge portions arranged for holding down work on said work support, and means for aligning work on said work support prior to the impressing of material thereon.
13. A shoe ornamenting machine having work supporting means, means for impressing material on work, means having clearance for said impressing means for holding down work on said work support, and means for intermittently applying material to said impressing means.
14. In combination in a shoe ornamenting machine, a work support, means for impressing material on work positioned on said work support, means extending from said work support for aligning work on said support, and means for holding down work on said support having clearance for said aligning means.
15. A shoe ornamenting machine having a member for holding down a shoe part, said member having a perforation through which a decorative piece may be applied to the shoe part, and means for cementing the shoe part prior to the application of the piece.
16. For use in a machine for marking or cementing shoe upper materials, having a supporting head, the combination of a plate having an impressing die mounted on one side thereof and having three pins extending from the other side of the plate, said pins formed to project into openings in said head for locating the die plate, and one of said pins con-

structed and arranged to be clamped in said head.

17. For use in a machine for marking or cementing shoe upper materials, having a supporting head, the combination of a plate having a die mounted on one side thereof and having three pins extending from the other side, two of said pins formed to project into openings provided in the supporting head to locate the die and one of said pins being notched to be received and locked in said supporting head.

18. For use in a machine for marking or cementing shoe upper materials, having a supporting head with a locking lever associated therewith, the combination of a plate having a die mounted on one side thereof and having a plurality of aligning pins extending from the other, one of said aligning pins being notched to cooperate with said locking lever to clamp said plate to said head.

19. For use in a machine for marking or cementing shoe upper materials having a supporting head and a base, the combination of a gauge plate and a marking device, said marking device comprising a plate having an impressing die mounted on one side thereof and provided with means for attachment to said head comprising a plurality of aligning pins, one of which is notched for forming a quickly detachable mounting for said plate, and said gauge plate being constructed with abutments to align work relative to said impressing die, said gauge plate having a pin and socket mounting on said base.

20. For use in a machine for marking or cementing shoe upper materials having a supporting head and a base, the combination of a gauge plate and a marking device, said marking device comprising a plate having an impressing die mounted on one side thereof and provided with means for attachment to said head, and said gauge plate being constructed with abutments to align work relative to said impressing die, said gauge plate having a pin and socket mounting on said base, and a hold down plate associated with said gauge plate having openings allowing clearance for said impressing die and said work aligning abutments.

21. A shoe ornamenting machine comprising a non-yielding flat surfaced base, a removable work supporting member resting on said base and upon which a shoe part to be ornamented is supported, a work locating abutment associated with said member, a hold-down member having an opening, and an ornamenting instrumentality, said ornamenting instrumentality constructed and arranged for movement downwardly through the opening in the hold-down, whereby the work under the hold-down member is ornamented.

22. A shoe ornamenting machine comprising a non-yielding flat surfaced base, a work

supporting member resting on said base and upon which a shoe part to be ornamented is supported, a plate adapted to be pressed against the work having an opening, and an ornamenting instrumentality, said plate, work supporting member and ornamenting instrumentality constituting an ornamenting unit placeable in operative relation to said base, said ornamenting instrumentality being constructed for movement downwardly through the opening in the plate whereby the work positioned under the plate is ornamented.

23. A shoe ornamenting machine comprising a non-yielding flat surfaced base, a work supporting member resting on said base and upon which a shoe part to be ornamented is supported, a plate adapted to be pressed against the work having an opening, and an ornamenting instrumentality, said plate, work supporting member and ornamenting instrumentality constituting an ornamenting unit placeable in operative relation to said base, said ornamenting instrumentality being constructed for movement downwardly through the opening in the plate whereby the work positioned under the plate is ornamented, said plate having edges for positioning the work.
